STOP MOTION FOR SPINNING FRAMES

Frank E. Harding, Lawrence, Mass., assignor to
Arlington Mills, Lawrence, Mass., a corpora-
tion of Massachusetts

Application February 4, 1936, Serial No. 62,285

4 Claims. (CL. 117—30)

The present invention relates to stop motions for spinning frames and more particularly to lifter units of the general type disclosed in the patent to Arragg No. 2,044,238, granted June 16, 1936.

The principal object of the present invention is to provide improvements in the device of the Arragg application with a particular view to proper drafting of the roving. To this end, the present invention comprises the apparatus hereinafter described and particularly defined in the claims.

In the accompanying drawing, Fig. 1 is a side elevation of the preferred form of lifter unit; Fig. 2 is a rear view; and Figs. 3 and 4 are perspective views on a reduced scale, showing the mode of mounting the delivery roll bracket on the frame.

In the illustrated embodiment of the invention, the roving 6 passes between a positively driven lower back delivery roll 8 and a frictionally driven top back delivery roll 10 and thence through the carrier and front delivery rolls (not shown) in any suitable manner. The top delivery roll 10 is journaled in the side arms 12 of a yoke-shaped bracket 14. The arms 12 are connected by a top plate 16. The bracket is pivoted in a manner to be hereinafter described on a pin 18 in the main frame 20 of the lifter unit.

The frame 20 comprises a metal stamping having a back plate 22 adapted to be attached to a rail 24 which extends across the spinning frame. Near the top, the back plate is provided with a U-shaped recess 26 to accommodate the roving 6.

The parts thus far described are in general similar to those of the Arragg application above referred to. In the Arragg device, the roll 10 may wear out of true, or it may be improperly supported due to bearing wear or bending of the bracket, with the result that the roll 10 does not contact throughout its length with the lower roll 8, and the roving may be improperly drafted. According to the present invention, slight rocking adjustment of the delivery roll bracket is permitted, whereby the roll may properly accommodate itself to the lower roll 8. To this end, the rear edge of the top plate 16 is indented as indicated at 28, and the indentation seats in a small hole 30 in the upper edge of the frame 20. The pivot pin 18 passes through elongated vertical slots 32 in the side arms 12.

The upper delivery roll is pressed downwardly by a spring 34 surrounding a rod 36 and retained thereon by a nut 37. The spring bears against a washer 38 on the top plate 14. The plate 14 is provided with a slot 39 to permit assembly of the parts without removal of the spring. The rod 36 is offset, as indicated at 40, the lower end being received in a tongue 42 extending inwardly from the frame 20. The off-

set mounting of the rod permits application of the spring pressure at a point considerably forward of the pivot.

As in the Arragg application, the invention is provided with a lifter 44 pivoted on the frame 5 at 46 and padded at its forward edge with a piece of leather 48. The lifter is normally held free of the roll 10 by a latch engaging the lower end of the lifter and received within a magnet casing 50, but upon detection of roving breakage, the lifter is released, thereby engaging the pad 48 with the roll 10 to pinch the roving and at the same time to lift the roll 10 away from the lower roll 8.

The indentation 28 allows a limited rocking adjustment about an axis approximately perpendicular to the axis of the roll 10. This insures proper contact of the surface of the roll 10 with the lower roll 8, even though the roll 10 may, for any cause, be out of true with respect to the lower roll.

The invention having been thus described, what is claimed is:

1. A lifter unit for spinning frame stop motions comprising a frame, a delivery roll bracket 25 to receive a delivery roll, spring means acting on the bracket, and means for pivotally mounting the bracket on the frame constructed and arranged to permit a limited rocking adjustment of the bracket about an axis approximately perpendicular to the axis of the roll.

2. A lifter unit for spinning frame stop motions comprising a frame, a delivery roll bracket to receive a delivery roll, the bracket comprising side arms and a top plate, the side arms having 35 slots, a pivot passing through said slots and the frame, the top plate being formed to engage the frame only at the center to permit a slight rocking adjustment of the bracket, and a spring engaging the top plate to press the bracket downwardly.

3. A lifter unit for spinning frame stop motions comprising a frame, a delivery roll bracket to receive a delivery roll, the bracket comprising side arms and a top plate, the side arms having 45 slots, a pivot passing through said slots and the frame, the top plate being formed with an indentation to engage the frame and to permit a slight rocking adjustment of the bracket, and a spring engaging the top plate to press the 50 bracket downwardly.

4. A lifter unit for spinning frame stop motions comprising a frame, a delivery roll bracket having a top plate, a tongue extending inwardly from the frame below the top plate, a rod received in the tongue and offset toward the front, the top plate having a slot through which the rod passes, and a spring surrounding the rod and pressing downwardly on the top plate.
